UNITED STATES PATENT OFFICE.

AMMIE C. McARTHUR, OF CONNEAUT LAKE, PENNSYLVANIA.

COMBINATION-TRUNK.

No. 825,673.

Specification of Letters Patent.

Patented July 10, 1906.

Application filed January 24, 1906. Serial No. 297,674.

To all whom it may concern:

Be it known that I, AMMIE C. McARTHUR, a citizen of the United States of America, residing at Conneaut Lake, in the county of 5 Crawford and State of Pennsylvania, have invented certain new and useful Improvements in Combination-Trunks, of which the following is a specification, reference being had therein to the accompanying drawings.

10 This invention relates to certain new and useful improvements in combination-trunks; and the invention has for its primary object to combine a chiffonnier or dresser and a garment compartment or closet within a trunk, 15 whereby the trunk may be conveniently used as a chiffonnier or dresser, thereby providing a trunk particularly adapted for tourists and travelers who may be traveling in a remote part of the country where a chiffonnier or 20 dresser is not accessible.

Another object of this invention is to provide a novel trunk wherein a plurality of compartments are formed in which various garments may be placed, whereby they cannot 25 become creased or disfigured while being transported.

A further object of this invention is to combine a mirror and desk within a trunk, together with numerous compartments, whereby 30 the trunk may be used as a writing-desk or table at any time desired.

A still further object of this invention is to provide a combination-trunk which will be compact in form, strong and durable, and 35 comparatively inexpensive to manufacture.

The above construction will be hereinafter more fully described and claimed, and, referring to the drawings accompanying this application, like numerals of reference designate 40 corresponding parts throughout both views, in which—

Figure 1 is a perspective view of my improved trunk in an open position, illustrating the desk portion thereof, the dresser and the 45 garment closet or compartment; and Fig. 2 is a perspective view of the trunk closed.

To put my invention into practice, I construct my improved trunk of a shape similar to the ordinary type of trunk, with the exception that it may be slightly longer; but the shape and dimensions of the trunk are obvious, as the same may be made of various sizes for different purposes. The trunk comprises a body portion 1, having a hinged end 50 compartment 2, which is provided with a hinged lid or partition 3, having a mirror 4

arranged therein. The body portion of the trunk is formed with three transverse slideable drawers 5, having handles 6 6 and locks 7 of a conventional form. The end of the 60 body portion 1 of the trunk adjacent to the hinged end compartment 2 is provided with a small drawer 8 and a compartment 9, which may be used as a hat box or compartment. The compartment 9 is provided with a hinged 65 lid or partition 10. Slidably mounted between the drawer 8, compartment 9, and the uppermost drawer 5 is a slide or plate 11, which is pulled outwardly to serve as a desk or writing-pad.

70 The body portion of the trunk 1 is provided with a hinged lid 12, which is adapted to inclose the hinged end compartment 2, together with the drawers and various appurtenances of the body portion 1 of the trunk. 75 The lid 12 forms a garment closet or compartment 14, having hooks 15 arranged therein to support garments. The compartment 14 is provided with a hinged lid or partition 16, whereby the compartment 14 may be closed 80 irrespective of the body portion 1 of the trunk.

85 The entire trunk is preferably constructed of wood or leather and is bound by metallic strips 17, which are placed to protect the edges and corners of the trunk and the adjoining edges of the various compartments thereof.

When closed, the hinged end compartment 90 2 is adapted to fold into engagement with the body portion 1 of the trunk and be held in engagement therewith by the lid 12, which fits down over the adjoining edges of the hinged compartment 2 and the body portion of the trunk, it of course being understood that 95 the lid or partition 10 is closed, together with the desk-slide and the drawers 8 and 5 of the trunk.

100 When the trunk is used as a dresser and writing-desk, it is stood upon its one end and the lid 12 of the trunk swung open similar to the door of a closet. The hinged end compartment 2 is then swung upwardly to place the mirror 4 in a vertical position, whereby a person standing in front of the trunk can use 105 the same or any of the various compartments thereof, the body portion of the trunk, together with the end compartment 2 thereof, resembling very much a dresser when the trunk is open and being used.

110 I do not care to confine myself to the numerous compartments into which the trunk

may be subdivided, and such changes as are permissible by the appended claims may be resorted to without departing from the spirit and scope of the invention.

5 What I claim, and desire to secure by Letters Patent, is—

1. A trunk embodying a rectangular body portion, a plurality of drawers slidably mounted in said body portion, a desk slide or plate 10 mounted in said body portion, a hat compartment or box formed in said body portion above said desk-slide, and adjacent one of the drawers, said compartment having a laterally-opening hinged lid, an end compartment 15 hinged to said body portion, a lid hinged to the lower edge of said end compartment, a mirror arranged in the lid of the end compartment, a lid carried by the body portion of the trunk, and equal in length to 20 the combined height of the body portion and the end compartment and adapted to close said body portion and said end compartment, said last-named lid having a compartment

ment formed therein, a lid or partition hinged to the hinged edge of said last-named lid, and 25 adapted to close said compartment, substantially as described.

2. A trunk embodying a body portion and a hinged end compartment, said body portion having drawers slidably mounted therein, a desk slide or plate slidably mounted in said body portion, a mirror carried by said end compartment, a lid hinged to said body portion and equal in length to the combined height of the body portion and the end compartment and adapted to close said end compartment and said body portion, said lid having a compartment formed therein, substantially as described.

In testimony whereof I affix my signature 40 in the presence of two witnesses.

AMMIE C. McARTHUR.
